UNITED STATES PATENT OFFICE.

PERCY H. THOMAS, OF MONTCLAIR, NEW JERSEY, ASSIGNOR, BY MESNE ASSIGNMENTS, TO COOPER HEWITT ELECTRIC COMPANY, OF HOBOKEN, NEW JERSEY, A CORPORATION OF NEW JERSEY.

MERCURY-VAPOR OUTFIT AND CIRCUITS THEREFOR.

1,110,586.

Specification of Letters Patent. Patented Sept. 15, 1914.

Application filed March 30, 1905. Serial No. 252,797.

To all whom it may concern:

Be it known that I, PERCY H. THOMAS, a citizen of the United States, and resident of Montclair, county of Essex, State of New Jersey, have invented certain new and useful Improvements in Mercury-Vapor Outfits and Circuits Therefor, of which the following is a specification.

This invention is concerned with the construction and organization of vapor converters, a system of circuits suited for use with such converters, and regulating devices for the circuits.

In the drawings which illustrate the invention I have shown in considerable detail a convenient vapor converter outfit combined with switch-boards, ammeters, voltmeters and other devices suitable for connection with such an apparatus. I have also illustrated an appropriate system of circuits and also the arrangement of the regulating device above mentioned.

In the drawings, Figure 1 is a perspective view of a vapor converter outfit taken from a point at the rear of the supporting frame; Fig. 2 is a perspective taken from a point in front of the said frame; and Figs. 3, 4 and 5 are circuit diagrams.

Referring to the earlier figures of the drawing, it will be seen that the entire vapor apparatus is supported upon a horizontal frame, 1, having suitable legs or standards, 2, 2. At the forward end of the frame 1 are angular uprights, 3, 3, to which is secured by bolts or other suitable means, a plate, 4, of glass, porcelain, slate or other insulating material. The frame 1 itself is preferably formed of angular metal and the lower ends of the uprights 3 are secured to the vertical portion of the said frame. At the same time the upper ends of the uprights are braced by a cross-piece, 5, as shown. At the rear of the frame 1 an insulating switch-board, 6, is secured to uprights 7, 7, these parts themselves being bolted to the frame. The board 6 carries binding posts for making such connections as may be convenient in wiring up the converter and the associated operating parts. Between the uprights 3 and the sides of the frame 1 are braces, 8, 8, for giving strength and rigidity to the structure.

Underneath the frame 1 an inductance device, 9, is suspended by any suitable

means; and above the frame is mounted a 55 tilting magnet 10, the operation of which will be described hereinafter. A cut-out magnet, 51, is also placed above the frame. A vapor converter 11 is also mounted above the frame, the immediate means of support 60 being a horizontal cross-piece, 13, uprights, 12, 12 and a ring, 14, supported in a normally horizontal position by the said uprights. The upper part of the converter is held in position by an adjustable strap, 15, 65 the ends of which pass through lugs, 16, 16, on the ring 14 and are secured by nuts.

To the ring 14 is secured a lever, 17, carrying knife edges, one of which is shown at 18. These knife edges fit in saw-tooth 70 notches in the tops of the uprights, 12, one of said notches appearing at 19. The faces of the notches constitute limiting surfaces for the movement of the knife edges, thereby limiting the tilting of the converter as a 75 whole. To the lever 17 is pivoted an extension, 20, of the core, 21, of the tilting magnet 10. When the said magnet is energized it draws in the core 21 and tilts the converter through a certain distance as will 80 be explained further on in this specification.

The converter contains two solid electrodes, 22 and 23, and a mercury electrode, 24, which is the common negative electrode of the apparatus. A supplemental electrode, 85 25, is also present, being contained in a separate pocket, 26, and serving initially as a temporary negative electrode and afterward as a positive electrode for the device. The arrangement of these electrodes may 90 be seen by reference to Fig. 3.

I prefer to locate the electrodes 22 and 23 inside shields 50, 50, of insulating material, said shields being closed at the bottom and open at the sides which are remote 95 from each other, the object being to prevent short-circuits between the positive electrodes, when one of them is temporarily a negative electrode with respect to the other.

Immediately at the back of the switch-board 4 I place a regulating inductance device which comprises a laminated frame, 27, a coil, 28, and an internal laminated core, 29. The vertical position of the latter inside the coil 28 may be adjusted by hand through 100 the medium of a lever, 30, connected to the core 29 by a link, 31, and having an operating handle, 32, outside the switchboard 4.

I find it convenient to support the usual voltmeter, 33, and an ammeter, 34, on the front of the switchboard 4 and I also locate similarly knife switches, 35 and 36, the former of which controls the circuit to the load and the latter of which is adapted to throw a transformer (not shown in Figs. 1 and 2) into or out of connection with a primary source of alternating current.

10 The diagram appearing in Figs. 3 and 4 illustrates the circuits applied to the apparatus already described. Here the switch 36 is represented as controlling the circuit from the wires 37 and 38 leading to a source 15 of alternating current on its way to the primary, 39, of a transformer, the secondary of which is shown at 40. Between the switch 36 and the primary of the transformer I locate the coil, 28, already described. An auto transformer may replace the transformer shown.

The switch 35 controls the circuit extending from an intermediate point of the secondary 40 to one side of the load and passing from the other side of the load or work circuit to the main negative electrode 24 of the vapor converter 11. The load in this instance is represented as a storage battery 41 which is to be charged by the alternating source after the current has been rectified by passing through the converter 11. Between the storage battery and the electrode 24 an inductance, 42, is located and also the magnet, 51, which is adapted, when fully energized, to open a cut-out, 44, as shown. From the stationary terminal of the said cut-out extends a conductor, 45, which includes the coil of the tilting magnet 10 and also includes a resistance, 46. From the other side of the load or work circuit a conductor, 47, is branched off to the electrode 26 a resistance, 48, being included in said branch conductor.

The first action setting the converter into operation consists in closing the switch, 35, thereby throwing in the storage battery 41. A circuit is thus formed through the branch, 47, the resistances, 48 and 46, the magnet coil, 10, the cut-out, 44 and the cut-out magnet 51. Owing to the presence of the various resistances named, the magnet 51 does not act to operate the cut-out but the current in the described circuit does actuate the magnet 10 and tilt the converter 11 sufficiently to bring the mercury of the electrode 24 into contact with the mercury in the pocket 26. Thereupon a circuit is formed through the magnet 51 the inductance 42 the contacting electrodes 24 and 25, the resistance 48 and the conductor 47, thus short-circuiting the magnet coil 10 and allowing the converter 11 to tilt back to its original position, separating the electrodes 24 and 25, thus making the mercury at 24 a positive electrode with respect to the mercury in the

pocket 26. The alternating current having been thrown on by the closure of the switch 36, current may flow through the converter 11 from the electrodes 22 and 23 respectively, to the temporary negative electrode 25 and back to the middle point of the transformer secondary 40 through the several branches one of which is constituted by the conductor 47 and the resistance 48 and the other of which is constituted by the resistance 46, the magnets 10 and 51 and the battery 41. This current should be strong enough to energize the magnet 10 sufficiently to tilt the converter 11 until contact is again made between the electrodes 24 and 25, when the current from the positive electrodes 22 and 23 after entering the temporary negative electrode 25 will divide into two parts, the major portion passing through the electrode 24 and the coil 42 and then as before, the other portion through the electrode 25 and the resistance 48 and conductor 47 as before or through the branch 46, 10, 45, 44, as before. The connection between the electrodes 24 and 25 by this second tilting of the converter 11 largely shunts the current from the magnet 10 allowing the converter to tilt back a second time to its original position again separating the electrodes 24 and 25. This second separation causes the electrode 24 to be a negative electrode as well as the electrode 25, whereupon the positive electrodes 22 and 23 feed both the electrode 24 and the electrode 25 as negative electrodes. Thereafter the electrode 25 will be cut out of circuit by the operation of the magnet 51 on the cut-out 44. It is found in practice that the action of the magnet coil 10 is often such as to cause a double connection and disconnection between the electrodes 24 and 25 with a single tilt of the converter 11 which is the desirable adjustment. In such cases a second tilting of the apparatus is not necessary and cannot occur on account of the opening of the cut-out 44 by the passage of current through the magnet 51. The cut-out 44 might be inserted in the conductor 47 instead of in the conductor 45, as shown in Fig. 5, in which figure the cut-out 60 is located in the conductor 47 and corresponds to the cut-out 44 or a cut-out might be employed in both circuits. In the arrangement shown the cut-out in the circuit 47 is omitted since current will not be maintained in the negative electrode 25, due to the fact that there is no inductance in its circuit. The device shown at 62 is a counter-weight acting against the weight of the core 21 and its connected parts.

The ring 14 is made up of two or more relatively adjustable parts shown at 63 and 64. By means of this relative adjustability the ring as a whole may be adapted to converters of different sizes and furthermore

- the center of gravity of the apparatus balanced upon the knife edges may be made the same regardless of the quantity of mercury in the electrodes 24 and 25, or the exact form 5 of the containing chamber. For since the location of the center of gravity depends upon the relative weight, form and location of the container and the mercury of the electrode and parts rigidly connected thereto, 10 by adjusting the height of the container through the change of relative position of the parts 63 and 64, the position of the container, mercury and attached parts can be raised or lowered until the center of gravity 15 is at the desired point. This adjustment is readily made in view of the fact as shown in the drawing that the bulb has progressively increasing diameters in the neighborhood of its line of support.
- 20 In the induction regulator shown advantage is taken to obtain a wide range of adjustability of the greater efficiency of the air gap introduced in the magnetic circuit through the coil of the regulator when 25 placed within the center of the coil. It will be understood that the order of closure of the switches 35 and 36 is not necessarily that described herein, but both switches may be thrown on simultaneously or the alternating 30 current switch may be thrown on first. If the first tilting and self-restoring operation does not act to make the electrode 24 the true negative electrode of the device, the described operation may be repeated as many 35 times as may be necessary.
- By adjusting the lever 30 through the medium of the handle 32, the apparatus may be so regulated as to pass currents ranging in value between wide limits. For example, 40 I have in this way utilized the same vapor converter for transmitting currents running from 6 amperes to 30 amperes.
- It will be noted that the handle 32 is provided with a pawl, 60, engaging with 45 ratchet disks, 61, 61, to retain the lever 30 in the position to which it is moved through the action of a spring (not shown). The pawl itself may be readily released by hand for moving the handle to a new position.
- 50 I claim as my invention:
1. In a vapor converter, a plurality of positive electrodes, a main negative electrode, a supplemental electrode, and means for making the said supplemental electrode temporarily negative with respect to the main negative electrode.
  2. In a vapor converter, a plurality of positive electrodes, a main negative electrode, a supplemental electrode, means for making the said supplemental electrode negative with respect to the main negative electrode, and means for afterward shifting the converter, so as to make the said supplemental electrode positive with respect 65 to the main negative electrode.
  3. The combination with a vapor converter provided with a plurality of positive electrodes, a main negative electrode and a supplemental electrode, of a coil for tilting the converter to bring the main negative 70 electrode into temporary contact with the supplemental electrode, such coil being located in shunt to the short circuit temporarily formed by the said contact whereby the coil is deenergized during the continuance 75 of said short circuit.
  4. In a vapor converter, electrodes, and means for causing a temporary connection between the electrodes and subsequently a separation thereof, such means consisting of 80 a tilting magnet and connections whereby said magnet is deenergized during the continuance of said short circuit.
  5. In a vapor electric apparatus, main electrodes, and a supplemental electrode, 85 means for making the said supplemental electrode temporarily a negative electrode, such means including a tilting magnet traversed by current through the supplemental electrode, the said tilting magnet acting as 90 an inductance in the said circuit.
  6. In a vapor electric apparatus, main electrode and a supplemental electrode acting temporarily as a negative electrode, in combination with an inductance traversed 95 by current through the supplemental electrode together with connections for the main electrodes and starting connections including the said supplementary electrode and the said inductance.
  7. A standard support for a number of equivalent vapor devices having progressively increasing diameters in the neighborhood of the line of support, said devices containing mercury in varying quantities, 105 said support being adjustable to bear weight to support the vapor device on different horizontal planes, thus compensating for the varying quantities of mercury.
  8. In a vapor electric apparatus, a main 110 and a supplemental negative electrode, an inductance traversed by current through the supplemental electrode, in combination with a translating device having a counter electro-motive-force adapted to pass current to 115 said negative electrode temporarily.
  9. The combination of a vapor electric apparatus having a plurality of electrodes, a source of alternating current for supplying energy to said apparatus, an electro-motor device for tilting said apparatus, and means actuated by the tilting of said apparatus for short-circuiting said electro-motor device while the tube is tilted.
  10. The combination of a vapor electric 125 apparatus having a plurality of electrodes, an electro-motor device for tilting said apparatus, means actuated by the tilting of said apparatus for short-circuiting said electro-motor device to prevent further tilt- 130

ing, and mean for permitting the return of said apparatus to its initial position.

11. The combination of a vapor electric apparatus having a plurality of electrodes, a source of alternating current for supplying energy to said electrodes, an electro-motor device for tilting said apparatus to establish a metallic connection between two of said electrodes said connection forming a short-circuit for said electro-motor device, and means for permitting the return of said apparatus to its initial position.

12. The combination of an evacuated tube, a plurality of anodes and a cathode therein, an electromotor device for tilting said tube, and a contact member for coöperating with said cathode to short circuit said electromotor device.

13. The combination of a source of current, a vapor electric apparatus connected thereto, said apparatus having a cathode and a coöperating anode, an electro-motor device operative to tilt said apparatus until said electrodes come into contact, and current conductors for said device connected to said source in common with the electrodes, whereby said device is deenergized by contact of the electrodes.

Signed at New York, in the county of New York, and State of New York, this 28th day of March, A. D. 1905.
